UNITED STATES PATENT OFFICE.

MATHIAS CLEMENS, OF SHERBURN, MINNESOTA.

DESIGN FOR A DOUBLE CLEVIS.

53,408.

Specification for Design. Patented June 10, 1919.

Application filed December 23, 1916. Serial No. 138,682. Term of patent 7 years.

To all whom it may concern:

Be it known that I, MATHIAS CLEMENS, a citizen of the United States, residing at Sherburn, in the county of Martin and State of Minnesota, have invented a new, original, and ornamental Design for a Double Clevis, of which the following is a specification, reference being had to the accompanying drawing, forming part thereof.

The figure is a perspective view of a double clevis embodying my design.

I claim:

The ornamental design for a double clevis, as shown.

MATHIAS CLEMENS.

Witnesses:

A. G. BROWN,
FRANK COLLINS.
